UNITED STATES PATENT OFFICE

HUBERT K. DALTON, OF STAMFORD, CONNECTICUT

DESIGN FOR A SMOKER'S STAND OR ANALOGOUS ARTICLE

Application filed May 8, 1931. Serial No. 39,783. Term of patent 14 years.

To all whom it may concern:

Be it known that I, HUBERT K. DALTON, a citizen of the United States, residing in Stamford, in the county of Fairfield, and State of Connecticut, have invented a new, original, and ornamental Design for a Smoker's Stand or Analogous Article, of which the following is a specification, reference being had to the accompanying drawings, forming part thereof.

Fig. 2 is a fragmentary elevation showing a movable part of the hollow intermediate section of the stand pedestal in open position, and

Fig. 3 is a detail elevation of the upper end or top of the stand.

Among other obvious applications of my design intended to be embraced by the subjoined claim, the following are enumerated: smoker's stands; flower stands; merchandise display tables; household furniture tables; Radio cabinet tables, and analogous articles made of wood or metal.

I claim:

The ornamental design for a smoker's stand or analogous article, substantially as shown in the accompanying drawing and described.

HUBERT K. DALTON.
